HEADWEAR

Charles E. Lewis, Truro, Nova Scotia, Canada

Application April 19, 1934, Serial No. 721,283

4 Claims. (Cl. 2-195)

This invention relates to headwear and comprises a self-adjusting cap capable of elastic expansion and contraction to fit heads of varying sizes and shapes. More particularly, the invention resides in making the cap body of stretchable material and providing it with a headband of elastic fabric so that both the body portion and the headband will stretch under slight tension and will contract to their original size and shape when free to do so. Caps so made will stretch to fit several different sizes and shapes of heads without imposing objectionable pressure thereon.

Caps provided with headbands of leather or other relatively stiff and inelastic materials will not stretch except under heavy tension to fit heads larger than the size for which they are actually designed. When stretched under heavy tension they exert objectionable pressure on the head and become permanently enlarged. Such caps, while giving a satisfactory fit at the time of purchase, may subsequently prove too small or too large owing to a change in headsize due to growth or trimming of the hair. It is also well known that the fit of the ordinary cap is affected by changes in weather or atmospheric conditions. It is thus apparent that ordinary types of caps are not self-adjusting to ensure a comfortable fit under all circumstances, and it is the principal object of the present invention to provide a cap that will more adequately meet this requirement.

According to the present invention, the cap body is made of stretchable material and is supported on the head by means of a headband made of elastic fabric capable of considerable stretch under slight tension. In sewing the band in place the lower edge is stitched, under slight tension, to the edge portion of the cap body so that the remaining portion of the band is left free to contract to a more or less conical shape. The band thus forms an expansible wall defining a head receiving opening gradually decreasing in circumference from the lower to the upper edge of the band. In addition to its high degree of elasticity, which permits it to expand and grip the head without exerting objectionable pressure thereon, the band is much softer and flexible than the usual leather headband and is, therefore, a more comfortable fit on the head. Such softness and flexibility is preferably obtained by making the band from elastic yarn comprising a core of elastic material including a covering of relatively inelastic fibrous material in which the core is held in a tensioned or elongated condi-

tion. In the case of a cap equipped with a visor, stretching of the edge portion of the body portion to which the visor is attached is not desirable since this may lead to rupture of the stitches holding the visor in place. The present invention therefore contemplates, as one of its features, the provision of an inelastic strip which is sewn to and serves to reinforce and prevent stretching of the edge portion of the cap body to which the visor is attached without interfering with the stretchability of the remaining portion of the cap body.

A further feature of the present invention resides in the provision of an elastic strip extending around the rear and side portions of the cap body and having its ends joined to the ends of the aforementioned inelastic strip. The elastic strip here referred to is stitched in place between the body of the cap and an inturned edge to which the elastic fabric headband is secured and serves as a shaping and reinforcing strip without interfering with the stretch of that portion of the cap body to which it is secured.

A further feature of the invention resides in the provision of a sweat band which is stitched to the forward edge of the cap body and overlies the forward portion of the elastic headband to protect the latter from perspiration accumulating on the forehead of the wearer.

Proceeding now to a more detailed description of the invention reference will be had to the accompanying drawing, wherein—

Fig. 1 is a perspective view looking towards the bottom and one side of a cap made in accordance with this invention.

Fig. 2 is a sectional view taken substantially along line 2—2 of Fig. 1.

Fig. 3 is a fragmentary sectional view along the line 3—3 of Fig. 1.

As shown in this drawing the cap body 5 is provided with an inturned edge 6. A folded strip 7 is fitted on that portion of the edge 6 to which the visor 8 is attached. Strip 7 is made of substantially inelastic fabric and its opposite ends are carried a short distance rearwardly along the sides of the cap body to overlie the ends of a second strip 9. The latter extends around the rear and forwardly along the sides of the cap between the cap body and the inturned edge 6 and is made of elastic fabric capable of considerable stretch under slight tension. The visor presents the usual attaching edges 10 which are arranged to lie between the strip 7 and an endless headband 11 made of elastic fabric. The forehead engaging portion of the band 11 is pro-

ected by an overlying sweat band 12 which is co-extensive with the attaching edges 10 of the visor. The lower engaging edges of the bands 11 and 12 are sewn to the cap body 5 by two lines 5 of stitching 13 which also pass through the attaching edges 10 of the visor. One line of stitching 13 terminates at the ends of the sweat band 12 but the other serves to secure the whole length of the lower edge of the headband 11 to the co-extensive inturned edge 6 of the cap body. The strips 7 and 9 are also stitched to the in-turned edge of the cap body as indicated at 10 and 15.

As previously stated, the headband 11 has its 15 lower edge stitched to the cap body under slight tension so that the band tends to contract to the slightly conical shape shown in Fig. 2, thus providing an expansible head opening gradually decreasing in circumference from the lower to 20 the upper edge of the band. When the cap is applied to the smallest size of head for which it is designed there is just enough tensioning of the headband to cause it to conform to the exact contour of the head and to hold the cap securely 25 in place thereon without subjecting the wearer to uncomfortable pressure. The cap may also be worn with equal comfort on any of the larger head sizes for which it is designed. In this connection it will be understood that the headband, 30 because of the conical shape to which it is normally contracted, is capable of independent expansion to accommodate several different sizes 35 of heads without tensioning of the cap body. It will also be evident that the elasticity of the band will permit the tensioned lower edge thereof to stretch with the material of the cap body to 40 accommodate a further range of head sizes beyond those which can be taken care of by the independent expansion of the headband. The stretching of the material of the cap body to 45 accommodate heads of different sizes is desirably confined to that portion of the cap body disposed rearwardly of the juncture of the strips 7 and 9 since stretching of the remaining or front portion of the cap body to which the visor and elastic sweat band 12 are secured is not advisable.

owing to danger of disrupting the stitching 13 by which these parts are sewn in place.

Having thus described my invention, what I claim is:—

1. A cap capable of elastic expansion and contraction to fit heads of varying sizes and shapes, 5 said cap comprising a fabric body capable of substantial stretch under light tension, an endless headband of elastic fabric having its lower edge sewn, under tension, to the head engaging edge of the body, and a visor sewn to the aforesaid edges of the body and headband along the forehead engaging portions thereof.

2. A cap capable of elastic expansion and contraction to fit heads of varying sizes and shapes, 15 said cap comprising a fabric body capable of substantial stretch under light tension, a visor attached to the edge of the body along the forehead engaging portion of the said edge, an inelastic strip sewn to the aforesaid portion of the 20 body edge to which the visor is attached and an endless elastic headband sewn, along its lower edge, to the head engaging edge of the body.

3. A cap capable of elastic expansion and contraction to fit a range of head sizes and shapes, 25 said cap comprising a stretchable body, an inelastic strip sewn to a portion of the head engaging edge of the body, an elastic strip sewn to the remaining portion of said edge and to the ends 30 of the inelastic strip, an elastic headband extending entirely around the inside of the body and having its lower edge sewn to the aforesaid body edge, and a visor attached to that portion 35 of the body edge to which the inelastic strip is sewn.

4. A cap comprising a body of stretchable fabric provided with an inturned edge adapted to fit over and encircle the head, a visor and a strip of inelastic fabric sewn to the forehead engaging portion of said edge, a strip of elastic 40 material sewn to the remaining portion of said edge, and a headband comprising a strip of elastic material extending entirely around the inner side of the body and having its lower edge 45 stitched to said inturned edge.

CHARLES E. LEWIS.
